LATCHING DEVICE

Neligh Clair Coates, Kansas City, Mo.

Application February 9, 1948, Serial No. 7,262

11 Claims. (Cl. 51—272)

1

The present invention relates in general to latching devices and it deals more particularly with mechanism for detachably mounting an auxiliary guard or stripper on the main guard of a cutter wheel.

The present application is a continuation-in-part of my co-pending applications, Serial No. 705,825 filed October 26, 1946, and Serial No. 650,834 filed February 28, 1946, the latter application in turn being a division of application Serial No. 584,544, filed March 24, 1945 which issued as Patent No. 2,450,371, dated September 28, 1948.

In my earlier applications I disclosed masonry saws such as are employed in practice to cut bricks, tiles, stones and the like to the shapes and sizes needed for instance in building construction and furnace building. The cutting is performed by a disk-like tool rotating at high speed, the disk being formed of an abrasive such as silicon carbide or formed of steel alloy which is rimmed with the abrasive. It usually is desirable to supply a lubricant to the rim of the disk where it engages the work piece, and to this end it has been customary in the past to jet a liquid lubricant against the sides of the disk so that the liquid is carried to the rim by centrifugal force.

In order to shield the operator from the lubricant thrown outwardly from the rim and also to protect him from injury due to accidental physical contact with the cutter itself, it is the practice to provide a guard over the upper portion thereof. I have found it very desirable also to provide on the guard a pair of troughs paralleling the opposite faces of the disk to recover excess liquid and recycle it back onto the disk; in the event that the cutter disk breaks during operation as sometimes happens in practice, the troughs serve a further purpose of catching flying fragments that might otherwise injure the operator. One of the objects of the present invention is to provide an improved form of device for stripping excess liquid from the disk and guarding against accidental injury due to breakage.

In the course of normal operation sediment collects in the troughs as a result of cutting the kerfs in the masonry work pieces, and it is therefore necessary to remove the troughs from the guard periodically to clean them. Removal of the troughs also greatly facilitates changing cutters, for instance to accommodate the cutter to the type of masonry material being worked upon.

Having in mind the need for frequent removal of these units, another object of the present in-

2

vention is to provide an improved detachable connection; and an important feature resides in the particular construction and arrangement of my latching mechanism. Another feature resides in combining the two troughs in a single unitary structure hereinafter referred to as a stripper, which structure is readily attachable to and detachable from the guard disposed over the cutter disk, by means of my novel latching device.

10 A further object is to provide a latching device for a detachable member wherein the latch controlling element also serves as a handle by means of which the member is removed from its support. Another important feature resides in arranging the latch controlling element for movement between two extreme positions, said positions being such that the element can conveniently be employed as a handle to remove the member from its said support only in one of them, and said 15 one position being the unlatching position of the element while the other is the latching position.

Other objects and features will be apparent in the following description of the invention.

20 In the accompanying drawings which form a part of the specification and are to be read in conjunction therewith, and in which like reference numerals indicate like parts of the various views:

25 Fig. 1 is a side elevation of my stripper and its latching device, showing the stripper mounted on the hood or guard over an abrasive wheel.

Fig. 2 is a perspective view of the stripper and latching device.

30 Fig. 3 is an enlarged vertical cross-section taken along the line III—III of Fig. 1 in the direction of the arrows.

Fig. 4 is an enlarged vertical cross-section taken along the line IV—IV of Fig. 1 in the direction of the arrows and

35 Fig. 5 is a fragmentary horizontal cross-section taken on the line V—V of Fig. 4 showing the bail in horizontal position as indicated by dotted lines in Fig. 4.

40 Referring more particularly to Fig. 1, the numeral 10 identifies a thin disk or cutting wheel made of abrasive material. Fixedly mounted on a shaft 12 between two hub plates 14, the wheel is driven at high speed in the direction indicated by arrow 16 by means of a motor connected to the shaft. The drive connection is shown and described in detail in my co-pending applications and since it forms no part of the present invention, it has been omitted from the drawings for 45 the sake of simplicity.

It will be understood that the cutting of bricks, tiles and like articles is effected by advancing the articles against the lower rim of the rotating abrasive disk. For the protection of the operator the upper half of the cutter is shrouded with a rigid metal safety hood or guard 18, the opposite sides of the guard being disposed in parallel planes spaced laterally from opposite faces of the disk while the forward edge is curved to conform with the periphery of the disk.

In operation, a liquid lubricant is introduced continuously onto the opposite sides of the rotating cutter preferably by jetting it against the hub plates through a pair of inwardly directed nozzles 20. As it is applied, centrifugal force carries the lubricant outwardly along the flat sides of the cutter to the rim and there it is flung from the wheel substantially at a tangent. The liquid leaving the lower or exposed part of the wheel travels downwardly and rearwardly away from the operator while that leaving the upper part is caught by guard 18 and thus does not reach the operator.

It can readily be appreciated that the high speed at which the abrasive wheel turns causes it to set up strong currents of air adjacent its opposite faces and I have found in practice that this air stream sometimes diverts a substantial part of the liquid from the nozzles 20 before it reaches the surface of the wheel. To recover and make use of this lubricant as well as that flung from the rim of the wheel into the hood, a stripper 22 is detachably secured to the lower front edge of the hood.

The shape of the stripper may best be appreciated from Fig. 2. About its bottom 24 it has an upstanding marginal lip 26 adapted to embrace opposite sides and the end of the hood. The bottom contains a narrow slot 28 for receiving wheel 10 and around this slot there is an upstanding inner lip 30. Thus a trough for catching liquid is formed on either side of the wheel, the bottom of the trough inclining downwardly from the rim to the central part of the wheel as shown in Fig. 1 and terminating in a notch 32 through which a lubricant is adapted to drain back against the sides of the clamping collars 14. It will be noted that the portion of the inner lip which is adjacent the periphery of the cutter is beveled as shown at 33 to form a knife edge for stripping the excess lubricant clinging to the marginal edge of the rotating disk; this assures that only the proper amount for good lubrication is left on the disk.

In addition to recovering and recycling the lubricant against the cutter, the stripper has another extremely important function; should the abrasive disk break while running at high speed as sometimes happens, the stripper traps fragments that might otherwise be hurled outwardly from under the hood to injure the operator.

The forward end of my stripper is supported by pins 34 which project laterally from opposite sides of the hood into horizontal slots 36 in the marginal flange or lip 26. The opposite end is supported by the ends 38 of a bail 40 which project inwardly through registering holes in the stripper and hood as long as the bail is positioned as shown in Figs. 1 and 4. This, of course, is the normal position of the bail.

Adjacent the respective ends of the bail the sides of the stripper are provided with downwardly diverging surfaces 42 terminating in laterally projecting ears 44. In order to remove the stripper from the hood it is only necessary to

5 pivot the bail downwardly against the ears as shown in Fig. 5 and by dotted lines as shown in Fig. 2, and then draw the bail radially away from the axis of the cutter. Upon the downward rotation of the bail the wedging surfaces 42 spread the bail enough to withdraw the ends 38 from holes 36 in the hood; this releases the rear end of the stripper and the radial movement of the stripper causes slots 36 to retreat from pins 34

10 to release the forward end.

15 Replacement of the stripper on the hood is accomplished with equal ease. Slots 36 are once more introduced over pins 34 and the stripper is advanced until it occupies its Fig. 1 position. Then the bail is simply turned upwardly against the hood whereupon due to its own spring tension, the ends 38 immediately re-enter holes 36 latching the unit in place.

20 The ease and rapidity with which the stripper can be removed and replaced makes it a simple matter to clean out the sediment tending to accumulate in the stripper as the result of the abrasive cutting action carried out by the wheel; and frequent cleaning maintains the liquid recovery and recycling system at maximum efficiency. The disclosed latching arrangement also greatly facilitates interchanging cutter wheels on the machine.

25 From the foregoing it will be seen that this invention is one well adapted to attain all the ends and objects hereinbefore set forth together with other advantages which are obvious and which are inherent to the apparatus.

30 It will be understood that certain features and subcombinations are of utility and may be employed without reference to other features and subcombinations. This is contemplated by and is within the scope of the claims.

35 Inasmuch as many possible embodiments of the invention may be made without departing from the scope thereof it is to be understood that all matter herein set forth or shown in the accompanying drawings is to be interpreted as illustrative and not in a limiting sense.

40 Having thus described my invention, I claim:

1. In combination with a rotary cutter disk having a guard enclosing the upper portion of the disk, a stripper adapted to bridge the space between the disk and the edge of the guard, means 45 for detachably mounting the stripper on the guard, said means comprising a bail pivoted to the stripper, holes in the guard adapted to receive the ends of the bail; and means for withdrawing said ends from said holes responsive to a pivotal movement of the bail.

2. A combination as in claim 1 wherein said last means comprises inclined wedging surfaces on the stripper adjacent the respective ends of the bail.

3. A combination as in claim 1 having stops 60 limiting the pivotal movement of the bail with respect to the stripper.

4. In combination with a rotary cutter disk having a guard enclosing the upper portion of the disk, and elongated stripper adapted to bridge the space between the disk and the edge of the guard, means for detachably mounting the stripper on guard, said means comprising a pin and slot connection between one end of the stripper and the 65 guard, a bail pivoted to the other end of the stripper, holes in the guard adapted to receive the ends of the bail, and means for withdrawing said ends from said holes responsive to a pivotal movement of the bail.

70 5. A combination as in claim 4 wherein said

means is adapted to withdraw said ends from said holes only when the bail is substantially aligned with the slots of said connection.

6. In combination with a rotary cutter disk; a guard surrounding the upper portion of the disk; the side walls of the guard being spaced laterally from the sides of the disk and the lower edge of the guard being substantially radial to the disk's axis of rotation; a cover member having laterally spaced parallel flanges; the distance between the flanges being slightly greater than the distance between the side walls of the guard; means for removably securing the cover member to the guard so said flanges are outside the respective walls of the guard, said means including a pair of aligned holes in the opposite flanges registering with holes in the opposite walls of the guard, a bail having its ends in said holes, and inclined surfaces adjacent the opposite ends of the bail adapted to spread the bail responsive to a pivotal movement thereof about its ends thereby to withdraw said ends from the holes in the walls of the guard; said cover member having portions extending from said flanges underneath the lower edge of the guard and inwardly to a point adjacent the sides of the disk thereby to cover substantially the entire opening on either side of the disk.

7. A combination as in claim 6 including stops for limiting the pivotal movement of said bail about its ends.

8. In combination with a rotary cutter disk; a guard surrounding the upper portion of the disk; the side walls of the guard being spaced laterally from the sides of the disk and the lower edge of the guard being substantially radial to the disk's axis of rotation; a cover member having laterally spaced parallel flanges; the distance between the flanges being slightly greater than the distance between the side walls of the guard; means for

removably securing the cover member to the guard so said flanges are outside the respective walls of the guard, said means including pins projecting laterally from the guard, slots in the flanges slidable over the pins, aligned holes in the opposite flanges thereupon registering with holes in the opposite walls of the guard, a bail having its ends in said holes, and inclined surfaces adjacent the opposite ends of the bail adapted to spread the bail responsive to a pivotal movement thereof about its ends thereby to withdraw said ends from the holes in the walls of the guard; said cover member having portions extending from said flanges underneath the lower edge of the guard and inwardly to a point adjacent the sides of the disk thereby to cover substantially the entire opening on either side of the disk.

9. A combination as in claim 8 wherein said surfaces are so inclined as to spread the bail when the bail is aligned with said slots.

10. In combination with a member having aligned holes on opposite sides thereof, a frame adapted to embrace said opposite sides, a bail pivotally mounted in said frame and having axially aligned ends registering with the holes, and means for moving the ends of the bail axially responsive to a pivotal movement of the bail with respect to the frame.

11. In combination with a member having aligned holes on opposite sides thereof, a frame adapted to embrace said opposite sides, a bail pivotally mounted in said frame and having axially aligned ends registering with the holes, and an inclined wedging surface adjacent each end of the bail for moving the ends axially responsive to rotation of the bail about its ends.
